INDEX TAB AND SUPPORTING STRIP

Wallace E. Figuccion, Louisville, Ky.

Application June 3, 1944, Serial No. 538,680

3 Claims. (Cl. 40—20)

This invention relates to index tabs adapted to be applied to the pages of books and has for its object to provide an improved form of index tab as well as a novel means for preserving such tabs for later use.

An important object of my invention is to provide an index tab comprising a heavy paper or light cardboard section bearing an index character and a strip of transparent material coated on one side with normally tacky pressure-sensitive adhesive (such, for example, as the material known as Scotch tape), folded over and secured to opposite faces of the index section and having its ends extended to form gummed wings for attachment to the marginal edge of a page. By reason of this construction, the use of a solvent is not required in attaching the tab to the page of a book; also, the index section is protected against soiling by the transparent covering of Scotch tape and, additionally, the wings which may overlie a portion of the printed matter when the tab is applied to the page of a book does not obscure or conceal such printed matter.

Another object of my invention is to provide a novel method of preserving for later use the form of index tab described above. This method consists in rendering one surface of a sheet of suitable material smooth and stable and then extending the two wings of the tab outward in opposite directions and adhesively applying the gummed surfaces of both wings to the smooth stable surface of the said sheet. The index section of the tab, which extends upward and at substantially right angle to the wings when the tab is mounted on the sheet, may be folded over one of the wings to expose the index characters. By being preserved in this way, the tab is protected against injury to its gummed wings, and, at the same time, the tab may be removed from the supporting sheet easily and quickly and with the adhesive coating upon its wings in a fresh tacky condition for ready application to the page of a book.

Still another object of my invention is to provide a novel strip for the supporting of the form of index tabs described above. In its preferred form this strip comprises a sheet of Cellophane or a similar material having a stiff backing of cardboard and the tabs are adhesively applied to the exposed surface of the sheet of Cellophane in the manner described above. In removing a tab from this strip, the index section of the tab is grasped by the fingers and pulled, causing the gummed wings to draw free from the Cellophane

surface of the supporting strip without losing any substantial portion of their adhesive coating.

Other objects and advantages will be apparent from the following detailed description of a preferred embodiment of the invention, reference being had to the annexed drawing in which:

Figure 1 is a perspective view of an index tab;

Figure 2 shows the manner in which the index tabs are manufactured en groupe prior to cutting the tabs apart;

Figure 3 shows a supporting strip and the manner in which the index tabs are attached to the strip; and

Figure 4 is a cross-sectional view through the supporting strip and tabs on the line 4—4 of Fig. 3.

Referring to the drawing, in Fig. 1 is illustrated an index tab 1 comprising a section 2 of heavy paper or cardboard upon one face of which is imprinted an index character 3. A short strip 4 of transparent gummed tape of the type known as Scotch tape—that is, Cellophane having a coating 5 of pressure-sensitive adhesive upon one side—is intermediately folded so as to overlie 20 the two faces of the index section 2, the coating of adhesive upon this strip serving to secure the strip to the index section. The ends of the strip project beyond one side edge of the index section and form wings 6 adapted to overlie opposite surfaces of a page 7 (indicated in broken lines) and be adhesively secured thereto by pressure alone.

In Fig. 2 is illustrated the manner in which the index tabs are manufactured. A narrow web 2a of heavy paper or light cardboard is printed 35 with a longitudinal row of index characters 3, these characters being suitably spaced apart. A transparent sheet 4a of Cellophane is provided with a coating 5a of pressure-sensitive adhesive upon one of its sides and is folded around the web 40 and gummed thereto. The marginal edges of the sheet 4a project beyond a side of the web and form wings 6a. The individual tabs, corresponding to that illustrated in Fig. 1, are formed by severing the composite Cellophane sheet and paper web along the dotted line indicated at 10.

In Figs. 3 and 4 is illustrated a method of preserving index tabs of the type described above. A supporting card is made up, said card comprising a stiff sheet 9 made of any suitable light material, such, for example as cardboard, and a sheet 8 of Cellophane laid over one surface of the stiff cardboard sheet and firmly secured thereto by means of an adhesive coating 11, the cardboard sheet forming a stiff backing for the sheet of Cellophane. The gummed wings 6 of the tab

are extended outward in opposite directions (as shown in Fig. 2) and are pressed down upon the exposed Cellophane surface of the supporting card so as to cause them to adhere thereto and the index section 2 is folded down over one of the wings in a manner such as to expose the index characters 3 to view, as indicated in Figs. 3 and 4. The tabs are secured to the supporting strip in a longitudinally-extending row so as to present an attractive appearance, and when a tab is to be removed the index section 2 is grasped by the fingers and a pull exerted sufficient to draw the wings 6 away from the supporting strip and during such withdrawal the wings curl slightly away from each other so as to freely allow these gummed wings to be inserted over the edge of the page 7 to be indexed (Fig. 1) and to be affixed thereto by pressure.

By using Cellophane for the surface of the supporting strip the cohesion between this strip and the adhesive coatings on the wings is insufficient to cause any substantial portion of said coatings to be stripped from the tabs during removal of the tabs from the strip so that this adhesive remains on the wings and affords means for the attachment of the tab to the page of the book to be indexed.

The tabs comprising the alphabet, series or group may be applied to both sides of the strip assuming that the strip has been rendered smooth and stable on its opposite sides, and if desired the strip may be attractively designed suitably provided with advertising matter so as to serve as a book marker or insert after the tabs have been removed therefrom.

While I have mentioned Cellophane as the material for the surface of the tab supporting strip, it will be apparent that other materials may be used instead, to reduce the cohesion between the tab and the strip.

Manifestly the invention is capable of being embodied in other forms than that described above without departing from the spirit of my invention as defined in the following claims.

I claim:

1. A means for supporting index tabs, a tab of the type comprising a section of flat material bearing an index character upon one of its faces, a strip of Cellophane folded over the front and back faces of said tab section and adhesively secured thereto and having the ends of the strip extended beyond an edge of said tab section and provided with an adhesive coating upon its opposed faces, said supporting means comprising a stiff sheet of the character of cardboard and a sheet of the character of Cellophane laid over one surface of said cardboard sheet and adhesively secured thereto, the ends of the Cellophane strip which forms a part of the tab being adhesively secured to the exposed Cellophane surface of the supporting means.
2. A means for supporting and preserving index tabs, a tab of the type having two attachment wings of Cellophane and a normally tacky pressure-sensitive adhesive composition upon the opposed faces of said attachment wings, said means comprising a stiff sheet of the character of cardboard and a sheet of the character of Cellophane laid over one surface of the said cardboard sheet and adhesively secured thereto, the two Cellophane wings of the tab being adhesively secured to the exposed surface of the Cellophane sheet of the supporting means.
3. A means for supporting index tabs, a tab of the type having two attachment wings of Cellophane and a normally tacky pressure-sensitive adhesive composition upon the opposed faces of said attachment wings, said means comprising a stiff backing sheet of the character of cardboard and a thin surface sheet of smooth stable material firmly united with said backing sheet, the Cellophane wings of the tab being adhesively secured to the smooth stable surface of the supporting means.

WALLACE E. FIGUCCION.
